DESIGN FOR A GRAND PIANO

Everett Worthington, Scarsdale, N. Y., assignor
to Story & Clark Piano Company, Chicago, Ill.,
a corporation of Delaware

Application February 8, 1938, Serial No. 74,972

Term of patent 7 years

To whom it may concern:

Be it known that I, Everett Worthington, a citizen of the United States and resident of Scarsdale, in the county of New York and State of New York, have invented a new, original, and ornamental Design for a Grand Piano, of which the following is a specification, reference being had to the accompanying drawing, forming a part thereof.

Fig. 1 is a top plan view of a grand piano, showing my new design.

Fig. 2 is a rear elevational view of said grand piano, with the legs shown broken away for purposes of illustration.

Fig. 3 is a similar side elevational view of the left side of the said grand piano, with the legs shown broken away for purposes of illustration.

Fig. 4 is a similar side elevational view of the right side of said grand piano, with the legs shown broken away for purposes of illustration.

Fig. 5 is a front elevational view partly broken away.

The dominant features of my design are shown in solid black lines.

I claim:

The ornamental design for a grand piano as shown and described.

EVERETT WORTHINGTON.
